FINIAL

Daniel R. Moon, Oak Park, Ill., assignor to Newell
Companies, Inc., Freeport, Ill.

Filed July 26, 1972, Ser. No. 275,204

Term of patent 14 years

Int. Cl. D8—99

U.S. Cl. D8—212

FIG. 1.

FIG. 2.

FIG. 3.

FIG. 1 is a side view of a finial incorporating my new design.

FIG. 2 is an end view of the finial as seen from the right in FIG. 1.

FIG. 3 is a sectional view taken along the line 3—3 in FIG. 1.

The broken lines are for illustrative purposes only.

I claim:

The ornamental design for a finial, as shown and described.
